UNITED STATES PATENT OFFICE.

FRANK L. GORMLEY, OF BROOKLINE, MASSACHUSETTS, ASSIGNOR TO A. O. NORTON, INC., OF BOSTON, MASSACHUSETTS, A CORPORATION OF MAINE.

SELF-LOWERING JACK.

Application filed October 26, 1921. Serial No. 510,538.

To all whom it may concern:

Be it known that I, FRANK L. GORMLEY, a citizen of the United States of America, and a resident of Brookline, in the county of Norfolk and State of Massachusetts, have invented certain new and useful Improvements in Self-Lowering Jacks, of which the following is a specification.

This invention relates to lifting jacks and particularly to high speed jacks and has for its object the provision of means for controlling the lowering of the jack under the load supported thereby.

The present invention is an improvement on the invention shown and described in U. S. Patent No. 1,329,665 issued Feb. 3, 1920, to J. C. Kopf and F. H. Schwerin.

The invention consists of certain novel features of construction and arrangement of parts which will be understood readily by reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which the invention consists can be variously arranged and organized and the invention is not limited to the precise arrangement and organization of these instrumentalities as herein shown and described except as required by the scope of the appended claims.

Of the drawings:

Figure 1 represents a vertical section of a lifting jack embodying the principles of the present invention.

Figure 2 represents a section of same on line 2, 2, on Fig. 1.

Figure 3 represents a vertical section of the braking mechanism.

Figure 4 represents an elevation of the braking mechanism, and

Figure 5 represents a horizontal section on line 5, 5, on Fig. 2.

Similar characters indicate like parts throughout the several figures of the drawings.

In the drawings, 10 is the base of a lifting jack having the upwardly extending cylindrical standard 11 provided with bearing surfaces 12 for the cylindrical ram 13

adapted to be moved vertically relatively to 55 said standard 11.

The upper end of the ram 13 has secured thereto a head 14 and in the lower end of said ram is fixedly secured a nut 15.

Extending through the nut 15 is a rotatable screw 16 having a steep pitch helical thread.

The lower end of the screw 16 has secured thereto a plate 17 resting on anti-friction members 18 supported by a fixed 65 plate 19 mounted in the base 10.

Above the plate 17 and keyed to the screw 16 is a gear 20 which meshes with a pinion 21 keyed to the shaft 22 parallel with the screw 16 and having reduced ends mounted 70 in bearings 23 and 24 within an annex section 25 secured to one side of the casing 10, 11, by bolts 26.

The shaft 22 has also keyed or otherwise secured thereto, a bevel gear 27 meshing 75 with a bevel pinion 28 rotatable with the lifting shaft 29 extending laterally from the annex section 25.

This lifting shaft 29 has a bearing in the gland 30 and its outer end is flat-sided, as 80 at 31, to receive the usual operating mechanism which may be of any well-known construction.

Midway of the shaft 22 is a bearing 32 therefor and above this bearing said shaft 85 has keyed or otherwise secured thereto the ratchet 33.

Above said ratchet 33 and loosely mounted on the vertical shaft 22 is a worm gear 34 having a downwardly extending 90 flange 35 in which are mounted the pawls 36 pivoted at 37 and forced into engagement with the teeth of the ratchet 33 by springs 38.

A worm 38 meshes with said worm 95 gear 34.

As thus far described, the construction is substantially identical with that shown and described in the before-mentioned patent except that in the present construction the 100 pitch of the worm 38 is sufficient to permit the said worm 38 to be rotated by the worm gear 34 when the load is being lowered and the vertical shaft is rotating in a reverse direction and by the engagement of the 105 pawls 36 with the teeth of the ratchet 33 is imparting rotary movement to the worm gear 34.

The worm 38 is secured to a shaft 39 revolubly mounted in suitable bearings in the annex 25, said shaft having secured to one end thereof a worm wheel 40 in a chamber 5 41 formed in the annex 25 and closed by the cover plate 41* secured to the annex 25 by bolts 42.

The teeth of the worm wheel 40 mesh with a worm 43 secured to and revoluble 10 with the shaft 44 revolubly mounted in suitable bearings formed in the annex 25.

The opposite end of the shaft 44 has keyed thereto a brake disk 45 partially surrounded by two brake arms 46 pivoted at 15 47 to the annex 25.

The annex 25 is provided with two curved ribs 48 partially surrounding the brake arms 46 and protecting said arms from injury.

20 Between the lower free ends of the arms 46 is a cam block 49 having flat sides normally in contact with the inner faces of the arms 46 as indicated in Fig. 4, the arms being normally retained in this position by 25 the springs 50 interposed between said ribs 48 and the arms 46.

The cam block 49 is mounted upon a stud 51 secured in the annex 25 and has depending therefrom the operating handle 52 by 30 which the block 49 may be turned about the axis of the stud 51 to separate the arms 46 from contact with the periphery of the brake disk 45.

When the load has been lifted, the operating device on the shaft 29 may be removed or may be disengaged in the usual manner 35 so that said shaft 29 will be free to rotate in the reverse direction provided the frictional contact of the brake arms 46 on the disk 45 is not sufficient to prevent the rotation of the said brake disk 45.

In other words, owing to the ratio of the gears between the brake wheel 45 and the screw 16, a slight frictional contact upon 45 the wheel 45 will be sufficient to retain the load in elevated position.

When it is desired to lower the load the operator actuates the handle 52 and by turning the cam block 49 about the axis of the stud 51 he causes the arms 46 to be moved about their pivots 47 thereby reducing the frictional contact on the brake wheel 45 sufficiently to permit the ram to run down under the load.

55 Should the ram lower at too great a speed, more friction may be applied by manipulating the handle 52.

It is obvious therefore that by this construction the operator may easily control the 60 downward movement of the ram and cause it to move at any desired speed.

The downward movement of the ram will be immediately stopped when the operator releases the handle 52.

65 When pressure upon the operating handle

is released, the springs 50 return the block to its normal position as indicated in Fig. 4.

When it is desired to lift a load supported upon the head 14, an operating device is placed upon the part 31 of the operating 70 shaft 29 and when said operating device is actuated the lifting screw 16 will be rotated clockwise and in its rotation will act upon the nut 15 and cause the ram 13 to be elevated.

75 The rotary movement of the shaft 29 is transmitted to the screw 16 by means of the bevel gears 28, 27 and spur gears 21, 20.

The gear 27 being keyed to the shaft 22, said shaft 22 is caused to rotate during the 80 lifting of the load in the direction of the arrow on Fig. 5 of the drawings.

The ratchet 33 will at this time ride over the pawl 36 and no movement will be imparted to the gear 34 as during the lifting 85 movement the brake arms 46 are in sufficient frictional contact with the brake wheel 45 to prevent the rotation of said wheel and the shaft 44 to which it is secured.

90 During the lowering of the load the screw 16 will rotate contra-clockwise and this rotary movement will be transmitted to the brake wheel 45 through the gear 20 and the pinion 21 to the shaft 22 which will be 95 rotated in a direction opposite to that indicated by the arrow on Fig. 5.

This reverse rotation of the shaft 22 will cause the teeth of the ratchet 33, secured to said shaft 22, to engage the pawls 36 and 100 impart rotary movement to worm gear 34, worm 38, worm gear 39, worm 43 and the shaft 44 to which the brake wheel 45 is keyed.

105 It must be understood that the thread of each worm 38 and 43 has a sufficiently steep pitch to permit them to be rotated by the rotation of the worm gears 34 and 39 with which they are respectively in mesh.

Owing to the reduction in gearing, the 110 brake wheel 45 will be rotated at considerable speed if the brake arms 46 are entirely removed from contact therewith but if the brake arms are retained in frictional contact with said wheel the speed 115 of lowering may be regulated readily even under the heaviest load by simply increasing or decreasing the frictional contact between the arms and wheel as desired.

115 It is believed that the operation and many 120 advantages of the invention will be understood without further description.

Having thus described my invention, I claim:

1. In a device of the class described, a 125 standard; a ram reciprocable therein; a nut in said ram; a rotatable screw in said nut; a shaft parallel with said screw; intermeshing gearing between said shaft and screw; means for rotating said shaft to elevate 130

the ram; a worm gear loosely mounted on said shaft; an over-running connection between said shaft and worm gear adapted to impart rotary movement to said worm gear only during the lowering of the ram; a worm adapted to be driven by said worm gear; a brake wheel; means for creating friction on said brake wheel; and gearing for transmitting rotary movement from said 10 worm to said brake wheel.

2. In a device of the class described, a standard; a ram reciprocable therein; a nut in said ram; a rotatable screw in said nut; a shaft parallel with said screw; intermeshing 15 gearing between said shaft and screw; means for rotating said shaft to elevate the ram; a worm gear loosely mounted on said shaft; an over-running connection between said shaft and worm gear adapted to 20 impart rotary movement to said worm gear only during the lowering of the ram; a worm adapted to be driven by said worm gear; a brake wheel; means for creating friction on said brake wheel; a second worm 25 gear rotatable by said worm; a second worm rotatable by said second worm gear; and a shaft for said second worm on which said brake wheel is secured.

3. In a device of the class described, a 30 standard; a ram reciprocable therein; a nut in said ram; a rotatable screw in said nut; a shaft parallel with said screw; intermeshing gearing between said shaft and screw; means for rotating said shaft to elevate the 35 ram; a worm gear loosely mounted on said shaft; an over-running connection between said shaft and worm gear adapted to impart rotary movement to said worm gear only during the lowering of the ram; a worm 40 adapted to be driven by said worm gear; a brake wheel; brake arms normally coacting with said brake wheel; gearing for transmitting rotary movement from said worm to said brake wheel; and means for moving 45 said arms away from said brake wheel.

4. In a device of the class described, a standard; a ram reciprocable therein; a nut in said ram; a rotatable screw in said nut; a shaft parallel with said screw; intermeshing 50 gearing between said shaft and screw; means for rotating said shaft to elevate the ram; a worm gear loosely mounted on said shaft; an over-running connection between said shaft and worm gear adapted to 55 impart rotary movement to said worm gear only during the lowering of the ram; a worm adapted to be driven by said worm gear; a brake wheel; pivoted brake arms normally in contact with said brake wheel; 60 gearing for transmitting rotary movement from said worm to said brake wheel; and a manually actuated device for moving said arms away from said brake wheel.

5. In a device of the class described, a 65 standard; a ram reciprocable therein; a nut

in said ram; a rotatable screw in said nut; a shaft parallel with said screw; intermeshing gearing between said shaft and screw; means for rotating said shaft to elevate the 70 ram; a worm gear loosely mounted on said shaft; an over-running connection between said shaft and worm gear adapted to impart rotary movement to said worm gear only during the lowering of the ram; a worm 75 adapted to be driven by said worm gear; a brake wheel rotatable by said worm; pivoted brake arms normally in contact with said brake wheel; a cam member between the free ends of said arms; and means for moving said cam member to cause said arms 80 to be disengaged from said wheel.

6. In a device of the class described, a standard; a ram reciprocable therein; a nut in said ram; a rotatable screw in said nut; a shaft parallel with said screw; intermeshing 85 gearing between said shaft and screw; means for rotating said shaft to elevate the ram; a worm gear loosely mounted on said shaft; an over-running connection between said shaft and worm gear adapted to 90 impart rotary movement to said worm gear only during the lowering of the ram; a worm adapted to be driven by said worm gear; a brake wheel rotatable by said worm; pivoted 95 brake arms; springs for retaining said arms normally in contact with said wheel; and a manually actuated device for moving said arms from contact with the wheel.

7. In a device of the class described, a 100 standard; a ram reciprocable therein; a nut in said ram; a rotatable screw in said nut; a shaft parallel with said screw; intermeshing gearing between said shaft and screw; means for rotating said shaft to elevate the 105 ram; a worm gear loosely mounted on said shaft; an over-running connection between said shaft and worm gear adapted to impart rotary movement to said worm gear only during the lowering of the ram; a worm 110 adapted to be driven by said worm gear; a brake wheel rotatable by said worm; a member for creating friction on said brake wheel and normally in contact therewith; and a manually actuated device for moving said 115 member from contact with the wheel.

8. In a device of the class described, a standard; a ram reciprocable therein; a nut in said ram; a rotatable screw in said nut; a shaft parallel with said screw; intermeshing 120 gearing between said shaft and screw; means for rotating said shaft to elevate the ram; a worm gear loosely mounted on said shaft; an over-running connection between said shaft and worm gear adapted to 125 impart rotary movement to said worm gear only during the lowering of the ram; a worm adapted to be driven by said worm gear; a brake wheel rotatable by said worm; a member for creating friction on said wheel and 130

normally in contact therewith; means for breaking the contact between said member and wheel; and means for limiting the outward movement of said member.

5 9. In a device of the class described, a standard; a ram reciprocable therein; a nut in said ram; a rotatable screw in said nut; a shaft parallel with said screw; intermeshing gearing between said shaft and screw; means for rotating said shaft to elevate the ram; a worm gear loosely mounted on said shaft; an over-running connection between said shaft and worm gear adapted to impart rotary movement to said worm gear only during the lowering of the ram; a worm adapted to be driven by said worm gear; a brake wheel rotatable by said worm; pivoted arms partially surrounding said wheel; curved ribs partially surrounding said arms; 15 springs between the free ends of said arms and said ribs; a pivoted cam member between the free ends of said arms; and an operating handle for moving said cam about its pivot.

10. In a device of the class described, a standard; a ram reciprocable therein; a nut in said ram; a rotatable screw in said nut; a shaft parallel with said screw; intermeshing gearing between said shaft and screw; means for rotating said shaft to elevate the ram; a worm gear loosely mounted on said shaft; an over-running connection between said shaft and worm gear adapted to impart rotary movement to said worm gear only during the lowering of the ram; a worm 30 adapted to be driven by said worm gear; a train of gearing actuated by the rotation of said worm; a friction device for normally preventing the operation of said gearing; and means for varying the friction of 40 said device.

Signed by me at 746 Old South Bldg., Boston, Mass., this 25th day of October, 1921.
